UNITED STATES PATENT OFFICE.

JOSEPH S. FORETICH AND ELIAS L. GROOMS, OF GULFPORT, MISSISSIPPI.

EXTRACTING APPARATUS.

1,149,039.

Specification of Letters Patent. Patented Aug. 3, 1915.

Application filed July 5, 1912. Serial No. 707,911.

To all whom it may concern:

Be it known that we, JOSEPH S. FORETICH and ELIAS L. GROOMS, citizens of the United States, residing at Gulfport, in the county of Harrison and State of Mississippi, have invented new and useful Improvements in Extracting Apparatus, of which the following is a specification.

This invention relates to an extracting apparatus, more especially designed for extracting turpentine and other essential oils and rosin from wood, but adapted also for extracting the essential substances from other materials.

15. The object of the invention is to provide a simple, reliable and efficient type of apparatus for rapidly and economically extracting substances of the character named, and which is adapted for the use of a solvent in 20 connection with heat in the extracting operation and to enable the solvent to be recovered for repeated use.

25. The invention consists of the features of construction, combination and arrangement 30 of parts hereinafter fully described and claimed, reference being had to the accompanying drawings, in which—

Figure 1 is a diagrammatic side elevation, with parts in section, of an extracting apparatus constructed in accordance with our 35 invention. Fig. 2 is a top plan view of the same. Fig. 3 is a vertical longitudinal section through the extractor or retort on an enlarged scale. Fig. 4 is a vertical transverse section of the same. Fig. 5 is an end elevation of the extractor or retort showing the adjacent hinged door in open position, the solvent spray coil and coating screen appearing in transverse section.

40. In carrying our invention into practice, we provide an extractor or retort comprising a substantially cylindrical casing 1 normally open at its opposite ends and adapted to be hermetically closed by hinged doors 45 2 and 3, which are mounted to swing in a horizontal plane to open and closed positions and to abut when closed against suitable packing 4 at the ends of the casing. The bottom of the casing preferably slopes 50 to a certain degree toward its outlet end and is provided at such point with an opening below which is arranged a chamber 5 for the collection of the rosin and other heavier volatile constituents of the wood.

55. At the top of the casing is a dome or receptacle 6 to receive the turpentine, solvent

vapor and other lighter volatile constituents, which dome is in communication respectively through pipes 7 and 8 with condensers 9 and 10, the pipe 7 being provided with controlling valves 11 and 12 and the pipe 8 with a controlling valve 13. Disposed within the top of the casing is a screen 14 acting as a retarder to the discharge of the vapors, and also disposed in the top of the casing above the screen is a perforated spray pipe or coil 15 for supplying a suitable solvent to the material under treatment, which solvent is sprayed from the pipe and through the screen and is thus properly distributed to all portions of the casing. Said coil or pipe 15 is supplied with solvent through a pipe 16 leading from an elevated solvent reservoir 17, which pipe 16 is provided with a controlling valve 18.

Arranged within the bottom of the casing is a steam heating pipe or coil 19, which is supplied with steam through pipes 20, 21 and 22 having controlling valves 23, 24 and 25 from a main steam supply pipe 26 leading from a boiler or other suitable steam generator 27. A similar heating pipe or coil 28 is arranged in the bottom of the collection chamber 5 and communicates with the pipe 26 through a pipe 29 having a controlling valve 30. The casing 1 is provided with a liquid gage 31 for indicating the level of the solvent therein, while the collection chamber 5 is provided with a pyrometer 32 whereby the internal temperature may at any time be determined. It will thus be understood that the casing and collection chamber may be heated to any desired temperature to drive off the volatile constituents of the wood and vaporize the solvent and also to keep the 90 rosin and other solid constituents in a liquefied state.

The casing is provided at opposite sides with track rails 33 to support therein a carriage 34 provided with wheels 35 to run thereon. Supported by the carriage is a perforate drum 36 adapted to contain the charge of wood or material to be treated and having a suitable door 37 for the admission of the material and discharge of the refuse or residuum. The drum is fixed to a longitudinally extending hollow shaft 38 journaled at its ends in bearings 39 on the carriage, whereby said drum may be turned to receiving and discharge positions and revolved during the extracting operation. The shaft is hollow and provided with lat-

eral discharge apertures 40 for the introduction of solvent liquids, vapors or gases into the charge of material contained in the drum, to facilitate extraction of the volatile constituents thereof, and its perforated portion within the drum is inclosed by a perforate guard screen 41 which operates to uniformly distribute the solvent throughout the mass of the material, as well as to prevent the material from entering and choking the apertures 40.

The doors 3 and 4 are adapted to be held closed by swing bolts 42 on the casing adapted for engagement with notches 43 in said doors, and the door 3 is provided with a bearing 44 for a hollow drive shaft 45 which extends therethrough. The inner end of this shaft 45 is provided with a clutch or coupling member 46 adapted to engage a coacting clutch or coupling member 47 on the adjacent end of the shaft 38, which clutch members are adapted to be automatically coupled and uncoupled by the closing and opening movements of the door 3, whereby the drum may be connected with and disconnected from the drive shaft. The drive shaft may be driven in any suitable manner, as by means of a sprocket wheel 48 connected by a chain 49 with a sprocket wheel 50 on a main driving shaft 51 receiving motion from any suitable source of power. The outer end of the drive shaft is provided with a coupling 52 for connection with a pipe or tube leading from any suitable source of supply of the solvent agent to be used, and the engaging surfaces of the clutch members 46 and 47 are provided in practice with suitable packing to form a tight joint for the flow of the solvent without leakage.

In practice at least two carriages provided with rotary drums of the character described are employed, one of which will be arranged within the extractor casing for the treatment of its charge while the other is being filled with a charge for subsequent treatment. The carriages are entered into the retort through the doorway 2 from a track 53 having a hinged section 54 which may be thrown back to permit the door to be opened and closed. At this point the drum may be filled with the wood or material from an elevated hopper 55 supplied with material by a conveyer or elevator 56. After the material has been treated within the extractor, the door 3 is opened and the carriage run out upon a track 57 having a hinged section 58 which may be swung back to permit said door to be opened and closed. The refuse material may then be discharged from the drum through the outlet controlled by the door 37 into a pin 59, or the carriage may be run into a bleaching and drying device similar in general construction to the casing 1, where the material may be

bleached and dried and prepared for use as wood pulp for the manufacture of paper or for other purposes.

The rosin and other heavier volatile constituents of the wood collected in the chamber 5 pass outward through a discharge pipe 60 to a refiner (not shown) and thence to a still 61, the heating coil 62 of which is connected with the pipe 26 by a pipe 63 having a controlling valve 64. In this still the finer or lighter volatile constituents remaining with the rosin and other heavier products are vaporized and pass through a pipe 65 into a tertiary condenser 66. The pipe 60 is inclosed by a steam jacket 67 which may receive the waste steam from the coil 28 or be supplied with steam from the pipe 26 by means of a pipe 68 having a controlling valve 69, whereby the rosin and solid products may be kept heated and prevented from hardening and clogging the pipes while the extractor is in operation or shut down for repairs, so that such products may be treated and removed at any time. The still 61 is provided with a discharge faucet 70 for the discharge of the rosin into a suitable receptacle 71 and a drain pipe 72 having a controlling valve 73 connects with the jacket 67 for the discharge of the water of condensation therefrom. A pipe 74 having a controlling valve 75 communicates with the collection chamber 5 so that hot water may be admitted into said chamber to support the body of rosin and prevent the same from being discolored by the heat from the coil 28 and jacket 67.

The condensers 9, 10 and 66 are respectively provided with draw off valves 76, 77 and 78 and communicate respectively with separators 79, 80 and 81 in which the volatile products or spirits are separated from the solvent or moisture. The separator 79 communicates through a pipe 82 having a controlling valve 83 with a solvent recovery tank 84 connected by a pipe 85 having a controlling valve 86 with the storage tank 17. A pump 87 is arranged in the pipe 85 and may be driven by hand or steam power for elevating the solvent from the tank 84 to the reservoir 17 for repeated use. Pipes 88 and 89 having controlling valves 90 and 91 connect the separators 80 and 81 with tanks 82' and 83' in which the spirits or volatile products are conducted for subsequent use. A pump 92, supplied with steam through a pipe 93 from the boiler is connected with the condensers through a conducting pipe 94 and branch pipes 95, 96 and 97 having controlling valves 98 therein, for supplying or circulating the cooling water.

In operation, the carriage supporting the drum containing the charge of wood to be treated is run into the casing 1 and the doors 2 and 3 closed, after which steam is admitted through the pipe 20 to the coil 19 and

through the hollow shaft 38 to the drum 36 and the drum slowly revolved, whereby the steam is caused to freely and quickly penetrate the body of material and drive off the 5 spirits or vapors. As soon as the casing has been heated to the required extent to liberate the spirits, the valve 11 is opened together with the valve 12 for the flow of the vapors to the condenser 9 and separator 80, in which 10 the vapors are condensed and the spirits separated from the water of condensation and finally discharged into the receptacle 82'. After all the spirits and rosin which can be removed by the steam heat from the wood 15 are driven off, the valves 23, 11 and 12 are closed and valve 18 opened and the hydrocarbon or other cold solvent admitted through the spray pipe 15 and hollow shaft until the extractor casing is about one-third 20 full, when the valve 18 is closed, whereby in the continued rotation of the drum the solvent will be taken up and washed through the wood, thus extracting the remainder of the spirits and the rosin. The valves 13 and 25 25 are then opened, by which steam is supplied to the coil 19 to heat the extractor and vaporize the solvent, which passes with the extracted spirits out through the pipe 8 into the condenser 10, where the volatile constituents 30 are condensed and pass into the separator 83, from which the solvent is discharged into the tank 84 and the spirits withdrawn from the separator and stored in one of the tanks 82' or 83'. During this 35 stage or process of vaporizing the solvent the drum is rotated at high speed, whereby through the centrifugal action set up all of the liquids and rosins will be deposited upon the walls of the casing, leaving the wood 40 thoroughly dry and free from all of the solvent and extracted substances, the rosin discharging into the collecting chamber 5 as previously explained. The door 3 is then 45 opened and the carriage run out for the subsequent bleaching and drying treatment of the refuse wood for the purpose described or for its discharge into the bin 59 for any other intended use, after which another filled drum is run into the casing and the 50 extracting operation above described repeated. While the solvent is being evaporated the hot water is admitted into the chamber 5 through the pipe 74, when the rosin is drawn off, separated from the water and refined 55 and finally separated from the spirits contained therein in the still 61, the spirits passing through the pipe 65 into the condenser 66, while the rosin is drawn off through the faucet 70 into a suitable receptacle. 60

It will be seen from the foregoing description that our invention provides for the treatment of the wood by heat and a solvent in such manner as to insure the rapid 65 and economical extraction of the rosin and

all the volatile constituents, the thorough separation of the rosin and constituents in a highly pure state and the recovery of the solvent for further use. The mode of treatment described not only enables the thorough 70 extraction of the substances from the wood, but also the rapid treatment of the wood and substances in such a manner as to reduce time and labor as well as to prevent discoloration of any of the products from excessive 75 heat, the advantages of which will be apparent. Furthermore by the described mode of treating the rosin and other heavier products, it will be seen that these substances may be kept in a liquid state for an indefinite 80 period and prevented from becoming chilled and clogging the apparatus, as at such times when its immediate removal is not convenient and it is desired or found necessary to shut down the extractor for 85 cleaning or repairs.

We claim:

1. An extractor comprising a cylindrical casing, doors for closing the ends of said casing, horizontal track rails in the casing, 90 a carriage adapted to travel on said track rails, a shaft supported by the carriage and having passages for the flow of a solvent therethrough, a drum carried by and in communication with the shaft, a driving shaft journaled on one of the doors and adapted to be connected with said hollow shaft, means for heating the casing, and means for collecting and separating the 95 products. 100

2. An extractor of the character described comprising an outer vessel having a vapor outlet at its top and a rosin outlet at its bottom, a perforated rotary receptacle disposed longitudinally within and spaced at all sides 105 from said outer vessel, a perforated pipe or tube extending longitudinally within the vessel for the injection of an extracting agent throughout the mass of the material contained therein, said pipe or tube forming the supporting axis on which the perforated receptacle rotates, means for heating the interior of the outer vessel, and means for rotating said receptacle. 110

3. An extractor of the character described comprising an outer vessel, a door for closing the same, means for heating said outer vessel, track rails within the outer vessel, a carriage arranged to travel said track rails, a perforated pipe supported by the carriage, 115 a perforated receptacle mounted to rotate upon said perforated pipe as an axis, a drive shaft supported by the door, and means for connecting said shaft with the perforated pipe when the door is closed. 120

4. An extractor of the character described including a carriage, a perforated pipe or axle supported by said carriage, a perforated drum or receptacle carried by said pipe and through which the latter extends 130

axially, and a guard screen inclosing said pipe within said receptacle.

5. An extractor of the character described comprising an outer vessel having a vapor outlet at its top and a rosin outlet at its bottom, a heating coil disposed within the bottom of said vessel, a perforated solvent injecting tube arranged within the top of said vessel, a guard screen disposed beneath 10 said injection tube, a longitudinally extending perforated pipe, a rotary perforated receptacle disposed longitudinally within and in spaced relation to the vessel and through which the pipe extends axially, and means 15 for rotating said perforated receptacle.

6. An extractor including a casing, a collection chamber communicating with the bottom thereof, a steam heating coil arranged within said chamber, a still, a pipe 20 leading from the chamber to the still, a jacket surrounding said pipe, means for supplying steam to the coil and jacket, and

means for supplying water to the chamber to be heated to float the body of rosin therein.

7. An extractor including an extracting vessel provided with a vapor outlet at its top and a rosin outlet at its bottom, a heating coil within said vessel, a heating coil within the rosin outlet, a still, a pipe leading from the rosin outlet to said still, a jacket surrounding said pipe, means for supplying water to the rosin outlet to be heated to float the body of rosin therein, a steam supply pipe, and valved connections 30 between said steam supply pipe and the heating coils and jacket.

In testimony whereof we affix our signatures in presence of two witnesses.
